(57) **CLAIM**

The ornamental design for a positioning bed pad as shown and described.

DESCRIPTION

FIG. 1 is a perspective view of a positioning bed pad showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the positioning bed pad where the positioning bed pad is in a first configuration of use; and,

FIG. 10 is a perspective view of the positioning bed pad where the positioning bed pad is in a second configuration of use.

The long thick broken lines in the drawings depict stitching of the positioning bed pad that form no part of the claimed design. The short thin broken lines shown in FIG. 9 depict portions of the positioning bed pad that form no part of the claimed design. The remaining short thin broken lines shown in FIG. 10 depict environment of the positioning bed pad that form no part of the claimed design.

1 Claim, 10 Drawing Sheets
